Primary Examiner — Rosemary K Tarcza*Assistant Examiner* — James Thorn, Sr.(74) *Attorney, Agent, or Firm* — Douglas P. LaLone;
Fishman Stewart PLLC(57) **CLAIM**

The ornamental design for a watch, as shown and described.

DESCRIPTION

FIG. 1 is a perspective view of a watch of the present design; FIG. 2 is a front elevational view of the watch of FIG. 1; FIG. 3 is a rear elevational view of the watch of FIG. 1; FIG. 4 is a top plan view of the watch of FIG. 1; FIG. 5 is a right side elevational view of the watch of FIG. 1;

FIG. 6 is a left side elevational view of the watch of FIG. 1; FIG. 7 is a perspective view of a second embodiment of a watch of the present design;

FIG. 8 is a front elevational view of the watch of FIG. 7; FIG. 9 is a rear elevational view of the watch of FIG. 7; FIG. 10 is a top plan view of the watch of FIG. 7; FIG. 11 is a right side elevational view of the watch of FIG. 7; and,

FIG. 12 is a left side elevational view of the watch of FIG. 7.

The broken lines shown in the drawings are included for the purpose of illustrating environmental structure and form no part of the claimed design.
